(57) **CLAIM**

The ornamental design for a grille brow, as shown and described.

DESCRIPTION

FIG. 1 is an environmental perspective view of a grille assembly showing a grille brow according to a first embodiment of our new design;

FIG. 2 is a perspective view of the grille brow shown in FIG. 1 without the environmental elements;

FIG. 3 is a front view of the grille brow shown in FIG. 1;

FIG. 4 is a top view of the grille brow shown in FIG. 1;

FIG. 5 is a bottom view of the grille brow shown in FIG. 1;

FIG. 6 is an environmental perspective view of a grille assembly showing a grille brow according to a second embodiment of our new design;

FIG. 7 is a perspective view of the grille brow shown in FIG. 6 without the environmental elements;

FIG. 8 is a front view of the grille brow shown in FIG. 6;

FIG. 9 is a top view of the grille brow shown in FIG. 6; and,

FIG. 10 is a bottom view of the grille brow shown in FIG. 6.

The broken lines shown in the figures represent portions of the grille brow that form no part of the claimed design.
